SHIRT COLLAR BAND EDGE TRIMMER AND
NOTCHING MACHINE

Theodore Cohen, New York, N. Y.

Application June 29, 1936, Serial No. 87,884

6 Claims. (Cl. 164—19)

This invention relates to new and useful improvements in a shirt collar band edge trimmer and notching machine.

The invention has for an object the construction of a device as mentioned which is characterized by an arrangement adapted to notch shirt collar bands and then to trim these bands. The purpose of notching the bands is to provide guide marks so that the bands will be properly attached to shirts.

A further object of the invention is to provide an arrangement wherein the notching mechanism is resiliently supported and arranged to be moved into operative position to first notch the collar band, and an arrangement which causes die sections to function to trim the collar band.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a machine constructed according to this invention.

Fig. 2 is a front elevational view of Fig. 1.

Fig. 3 is an end elevational view of Fig. 2 looking from the right hand end.

Fig. 4 is a sectional view taken on the line 4—4 of Fig. 2.

Fig. 5 is a fragmentary enlarged detailed view of a portion of Fig. 4.

Fig. 6 shows a notched collar band resting upon the lower die section.

Fig. 7 shows another type of notched collar band resting upon the lower die section.

Fig. 8 is a plan view of a lower die section constructed according to a modification.

The shirt collar band edge trimmer and notching machine includes a pair of spaced members 10 and 11 which are slidably supported. A resilient means is provided for holding these members in a normally raised position. A pair of notching elements 12 and 13 are pivotally supported upon the members 10 and 11. A means is provided for pivoting the elements 12 and 13 together and into operative positions and includes a toggle construction 14. A die section 15 is arranged beneath the elements 12 and 13 and is cooperative with a complementary die section 16 arranged between the elements 12 and 13 and the elements 12 and 13. A means is provided

for moving the complementary die section downwards into engagement with the die section 15.

The spaced members 10 and 11 are each supported upon a rod 17 which engages through slots 18^a in vertical posts 18. These vertical posts 18^a are mounted upon a base plate 19. The slots 18^a extend in from the top ends of the posts and terminate above the bottom ends. The upper portions of the posts are threaded. Nuts 19 engage upon the upper ends of the posts and form abutments for springs 20 which have abutment strips 20^a attached on their top ends. These springs act against the rods 17 and are opposed to other springs 21 also acting against the rods but located beneath the rods. It is the springs 20 and 21 which resiliently support the rods 17. The outer ends of the rods 17 are provided with heads 22 to prevent their disengagement from the posts 18. The springs 20 and 21 are so set that the members 10 and 11 are held in a normally raised position.

The notching elements 12 and 13 each have pivots 23 on the top edges thereof engaging through the members 10 and 11. It is these pivots which pivotally support the notching elements.

The notching elements are in the form of flat plates, and upon the lower edges supporting notching pins 25. These notching pins are removable by reason of engaging into sockets 26 mounted on the plates. Screws 27 cooperate with the sockets in releasably holding the pins 25.

Between the notching elements 12 and 13 and at each of the ends there is the toggle construction 14. Each toggle construction comprises a pair of pivotally connected levers which are pivotally mounted at their outer ends to the members 12 and 13. A rod 30 connects with each of the toggles and extends outwards and continues into a connecting section 30^a which in turn is connected with an arm 31 pivotally supported at its far end 31^a upon a bracket 32 mounted on the base plate 19.

Intermediate of the ends of the arm 31 a cable 33 is pivotally connected therewith. This cable extends downwards over guiding pulleys 34 and connects with a foot pedal 35 which is hingedly connected upon the floor. This foot pedal may be manually depressed to draw the cable, which in turn pivots the arm 31 downwards. This motion is transmitted to the toggles 14 which draw the notching elements 12 and 13 together and simultaneously move the notching elements downwards into operative positions. Pins 36

project from the members 10 and 11 and limit the inward pivoting of the notching elements as indicated by the dot and dash lines in Fig. 4.

Pressure is applied to the member 30 causing the members 12 and 13 to pivot until the notching pins 25 engage the sides of the die 16 which acts as a guide, and prevents the members 12 and 13 from pivoting further. Pressure still being applied the members 12 and 13 no longer pivot so the pressure is then utilized to force the members 10 and 11 down forcing the notching pins 25 to punch V-shaped notches in the collar and they then slightly engage into the opening in the die 15. When the pressure is released the springs 20 force the members back to their original position. The members 12 and 13 are pivotally mounted so that they swing into an inoperative position when it is desired to stamp the collar out by using the die 16. If it were not for this mounting the members 25 would be in the way of the die 16 rendering the device inoperative.

While pressure is being applied to lower the pins 25 and the die section 16 the material from which the collar is being formed is manually held in a taut condition across the opening in the die section 15 to prevent the aforesaid elements from forcing the material into the opening.

The upper die section 16 is supported by an arm 38 which is attached to the top of the die section and continues into an upward extending portion 38^a, which in turn continues to a rearward extending portion 38^b which is attached at its end to a bracket 39 mounted upon the base plate 19. A cable 40' is connected intermediate of the ends of the portion 38^b and extends downwards over guiding pulleys 40 and connects with a foot pedal 41 which is pivotally mounted from the floor. When the foot pedal 41 is depressed the cable will be drawn and the motion transmitted to ultimately move the die section 16 downwards to engage into the opening in the die section 15. The die section is normally urged into a raised position by a spring 43 coaxial upon a rod 44 mounted upon the section 38^b and guided by an opening 45 extending through the bracket 39. The spring 43 acts between the bracket and the section 38^b.

The die section 15 is formed with slots 48 at the sides through which holding studs 49 projects. These holding studs may be loosened and the die section shifted as required, or the die section may be entirely removed. The die section 16 is shown in plan view in Fig. 1 and it should be noted that it is of a shape to include both the back portion and the front portion of a collar. The complementary die section 15 is of a co-operating shape. These die sections are adapted to stamp out a collar 50, as indicated in Fig. 6. The notching pins 25 form the notches 51 in the edges of the blanked out collar piece.

Fig. 7 shows a modification in which the blanked out collar section 50^a is merely one of the layers of a collar. This collar section is shown formed with notches 51.

In Fig. 8 a modified form of die is illustrated which is adjustable to produce collars of different sizes, for example, from size 14 to 17. The bottom die section 15^a is provided with a plurality of removable end pieces 52 and 53 which may be removed to increase the size of the opening in the die. Similarly, the complementary die section may be provided with similar pieces which may be added and removed as conditions warrant.

The operation of the device is as follows: Ma-

terial from which the shirt collar band is to be stamped is placed upon the bottom die section 15. The foot pedal 35 is depressed to cause the notching elements 12 and 13 to descend so that the notching pins 25 cut notches in the material. The pedal 35 is released and the notching elements 12 and 13 will move up to their normal position. The pedal 41 is then depressed which moves the die section 16 down to stamp out the collar band. It should be noted that in the stamped out collar band the notches 51 are within the edges of the blank.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A shirt collar band edge trimmer and notching machine, comprising a pair of spaced members slidably supported, resilient means for holding said members raised, a pair of notching elements pivotally supported between said members, means for pivoting said elements together into operative position, means for moving said pivoted elements downwards, a die section beneath said elements, a complementary die section between said elements, and means for moving said complementary die section downwards.

2. A shirt collar band edge trimmer and notching machine, comprising a pair of spaced members slidably supported, resilient means for holding said members raised, a pair of notching elements pivotally supported between said members, means for pivoting said elements together into operative position, means for moving said pivoted elements downwards, a die section beneath said elements, a complementary die section between said elements, and means for moving said complementary die section downwards, posts, rods slidably engaged in slots in said posts, said spaced elements being carried by said rods.

3. A shirt collar band edge trimmer and notching machine, comprising a pair of spaced members slidably supported, resilient means for holding said members raised, a pair of notching elements pivotally supported between said members, means for pivoting said elements together into operative position, means for moving said pivoted elements downwards, a die section beneath said elements, a complementary die section between said elements, and means for moving said complementary die section downwards, posts, rods slidably engaged in slots in said posts, said spaced elements being carried by said rods, and springs being arranged within said slots above and below the rods and comprising said resilient means.

4. A shirt collar band edge trimmer and notching machine, comprising a pair of spaced members slidably supported, resilient means for holding said members raised, a pair of notching elements pivotally supported between said members, means for pivoting said elements together into operative position, means for moving said pivoted elements downwards, a die section beneath said elements, a complementary die section between said elements, and means for moving said complementary die section downwards, posts, rods slidably engaged in slots in said posts, said spaced elements being carried by said rods, and

springs being arranged within said slots above and below the rods and comprising said resilient means, nuts being adjustably engaged upon said posts and form abutments for the other springs by which the tension of these springs may be adjusted.

5. A shirt collar band edge trimmer and notching machine, comprising a pair of spaced members slidably supported, resilient means for holding said members raised, a pair of notching elements pivotally supported between said members, means for pivoting said elements together into operative position, means for moving said pivoted elements downwards, a die section beneath 10 said elements, a complementary die section between said elements, and means for moving said complementary die section downwards, said means for pivoting said elements together comprises toggles mounted on the ends of the elements a pivotally mounted rod, rods connected at one end to said toggles and having their other 15 ends extending upwards and connected to said

rod, a cable being connected with the latter-mentioned rods, and a foot pedal being connected with said cable, said cable and foot pedal comprising the means for moving the pivoted elements downwards.

5

6. A shirt collar band edge trimmer and notching machine, comprising a pair of spaced members slidably supported, resilient means for holding said members raised, a pair of notching elements pivotally supported between said members, 10 means for pivoting said elements together into operative position, means for moving said pivoted elements downwards, a die section beneath said elements, a complementary die section between 15 said elements, and means for moving said complementary die section downwards, comprising a rod connected with the die section and continuing into a rod section pivotally supported, a cable connected with said rod section and extended over guiding pulleys, and a foot pedal 20 connected with said pedal.

THEODORE COHEN.
